COMBINED COFFEE AND GAMING TABLE

James V. Barron, 6244 Agnes Ave.,
North Hollywood, Calif.

Filed July 8, 1959, Ser. No. 56,706

Term of patent 14 years

(Cl. D33—14)

FIG. 1.

FIG. 3.

FIG. 2.

FIG. 1 is an exploded view of a table showing my design with the top removed therefrom;

FIG. 2 is a perspective view showing the top on the table.

FIG. 3 is an end view corresponding to FIG. 2.

The essential features of my design reside in the portions shown in full lines on the drawing. The design of the inner walls is continuous about the inner periphery like the end shown in FIG. 1.

I claim:

The ornamental design for a combined coffee and gaming table, substantially as shown and described.
